Knudsen, near Monroe, Wash.

Application July 18, 1939, Serial No. 285,056

4 Claims. (Cl. 255—46)

Our invention relates to percussion drills, intended primarily for rock drilling, and particularly to percussion drills of the type in which a rapidly rotating hammer, having impact elements projecting outwardly from a surface, engages complementary impact elements upon a striker which is in striking engagement with the end of the drill shank, thereby to effect rapid vibratory reciprocation of the drill shank in the direction of its length.

Such devices, as heretofore proposed, have been of two general types. In one such type the hammer is retracted by cam means, in opposition to a stiff spring, and is suddenly released; the hammer, when released, advances towards and strikes the striker with a force that is dependent primarily upon the stored force of the spring thus suddenly released. In the second type a rotative hammer element is engaged by the striker element, which is movable with relation to the hammer element, the hammer and the striker each having impact elements upstanding from their adjacent surfaces, sometimes of hardened ball or roller form, whereby with each impact the striker is repelled and caused to advance the drill bit through a working stroke; the force of each drill stroke is a function primarily of the rapidity of the striking impact. The latter type of drill, as heretofore employed, relies primarily upon very rapidly repeated light blows, rather than upon less frequent but heavier blows.

Certain objections have been encountered in practical operation of each of these types. In the first type, wherein the impact is produced by the release of energy stored in a spring, the spring is liable to break in time, because of fatigue of the material, and during operation it has a certain inherent periodicity which to some extent limits the periodicity of the vibrations and the force of the impact. Neither is it possible, with ease or certainty, to vary the force of the blows. In the second type, which involves rapidly repeated impacts between impact elements on the rotative hammer and on the reciprocative striker, perhaps in an attempt to lighten the tool, the hammer is of no large mass, and the weight of the blow it strikes is therefore largely or primarily dependent upon the weight, not of the hammer alone, but of the entire tool, which is itself and in its entirety set into rapid vibration by the repeated impacts. As mentioned, reliance for effectiveness is placed upon repeated light blows, rather than upon heavy blows. In both such types as heretofore proposed there has

been a great deal of seemingly unavoidable complexity, both in the tool itself and in its adjuncts, for instance in devices for supplying water to and through the hollow shank of the drill bit, thereby rendering such tools complicated and expensive.

One of the primary objects of the present invention is to simplify the structure of such tools and thereby to make them extremely rugged and far better suited to the conditions under which they will see service. This end is achieved in part by elimination of parts, and in part by materially increasing the mass of the hammer, as compared to the mass of the remaining parts.

It is a further object to provide such a tool in which the force of the impact, or the effectiveness of the drill, is in nowise controlled by the stored force of a spring, nor primarily by rapidity of impact, but primarily by the greater mass of the hammer initiating the impact as compared to the impacted parts of the tool.

It is a further object of the invention to provide such a tool which may incorporate the desirable features of prior devices, such as anti-friction rollers or balls, a rotative chuck or drill support, and water supply means, but which will be materially simplified and improved in the respects indicated above.

It is a further object to provide such a tool in which, at will and by simple means, it is possible to accomplish rotation of the bit intermediate each working stroke to a new position, or to permit the bit to remain without rotation.

It is a further object to provide such a drill, the principles whereof may be adapted to a tool in which the hammer and the striker are in axial alignment, or to a tool in which the hammer and the striker are disposed with the axis of one transverse to the axis of the other.

With these and other objects in mind, as will appear hereafter, our invention comprises the novel parts, and the novel combination and arrangement thereof, as shown in the accompanying drawings, described in this specification, and as will be more particularly defined by the claims which terminate the same.

In the accompanying drawings we have shown our invention embodied in forms which are at present preferred by us, it being understood that various changes may be made in the form, character, and arrangement of parts, within the scope of the invention as hereinafter defined by the claims.

Figure 1 is in general an axial section through a typical form of our device, and Figure 2 is a

section axially of the drill shank at right angles to the section of Figure 1, parts being omitted for clearer illustration.

Figure 3 is a general axial section through a modified form, and Figure 4 is a transverse section therethrough, substantially on the line 4—4 of Figure 3.

Essentially the tool consists of three parts—a rotative hammer 1, a striker 2, and a drill support or chuck 3, wherein the upper end of the shank of the drill bit 4 is supported. Thus supported, the end of the drill's shank engages, and is engaged by, the striker 2, and the latter is guided for movement towards and from a surface of the hammer 1, whereby impact elements 11 upon the hammer engage complementary impact elements 21 upon the striker to effect reciprocation of the striker 2 and of the drill 4 which is in engagement with the striker. Naturally it is necessary to provide a suitable support for the three essential elements, which support should be common to all of them, and to this end there is provided a casing 5, within which the hammer 1 is journaled, the chuck 3 is rotatively held, and the striker 2 is guided for movement in a direction lengthwise of the drill's shank. Preferably the striker is not permitted to rotate, and to this end a key 52 is held within the casing and engages within a keyway 25 in the striker. Since it is desirable that the drill support 3 be permitted to rotate, it is supported in rotative bearings 35 within the casing 5. The hammer 1 is likewise rotatively supported within the casing, and in the form of Figure 1 its axis of rotation is transverse to the axis of the drill shank 4, and hence it is supported by trunnioned ends 10 in radial bearings 55. In the form shown in Figure 3 the hammer 1' is rotative about an axis which coincides with the axis of the drill's shank, therefore it must be provided with end thrust bearings 54, which may also take radial thrust, or which may be supplemented with additional radial bearings 55'.

Insofar as certain functions, accomplishments and advantages of the invention are concerned, the impact elements 11 and 21 might take various forms. They might be, for instance, merely outstanding impact cams, raised above the adjoining surfaces of the hammer and of the striker, and incapable of movement each relative to its supporting member. They may also be in the form of balls, as shown at 11' and at 21' in Figures 3 and 4, or as shown at 11 and 21 in Figures 1 and 2, they may take the form of rollers. While cylindrical rollers are shown, other forms may be employed. The supporting member in each case is provided with a pocket for the reception and retention of each such impact element, while pocket and element are of such shape that the element may roll relative to the member which supports it, to present a fresh point or line of contact with each successive impact. Any suitable means to this end may be employed, such means being already known in the art.

It is desired to point out here that the hammer 1 is of large mass with respect to the striker and drill. The hammer, for instance, may weigh 50 pounds, of a total weight of perhaps 125 pounds for the entire device; in other words, the mass of the hammer represents a large proportion, preferably about 40%, as in the example given, of the whole mass. The striker 2 and drill 4 combined being of materially less mass than the hammer, the hammer has large inertia

opposing deflection from a given position, and relatively speaking, the striker 2 and drill 4 have materially less inertia resisting departure from a given position. The result is that the hammer 5 strikes an actual blow with each impact, and repels the striker 2 and drill 4 through the impact engagement of the elements 11 and 21, or 11' and 21', yet because of the simplification of the device, through omission of intricate or unnecessary parts, and through the omission of springs, the device as a whole is not of such great weight but what it can be carried about and used without undue difficulty. In particular it should be noted that because the inertia 15 of the massive hammer absorbs the greatest part of the shock of impact, that shock is not transmitted unduly to the device as a whole, and the latter does not vibrate with undue intensity. As a result a workman, supporting the device, 20 as for instance by the handles 53, is not unduly fatigued by rapid vibration, of appreciable amplitude, the amplitude of vibration of the striker and drill being much greater than that of the hammer and casing because of the large inertia 25 of the hammer.

It is desirable, after a hole is started, indeed necessary, to rotate the working point 49 of the drill bit to a fresh position frequently or substantially continuously. However, in starting a 30 hole it is preferable that the working point be not permitted to rotate, in order that it may achieve a start and not wander over the face of the work. The present invention, in either form, is designed to accomplish either of these 35 ends at will and by a simple adjustment.

Since it is necessary to allow the drill to be handled in use, hence to keep its total weight within reasonable bounds, notwithstanding the massive hammer, it is preferred to employ means 40 other than a self-contained motor to effect the necessary rotation of the hammer. Thus there is provided a coupling at 60 for a flexible drive shaft 6 or like means, extending from a distant motor (not shown). Journaled at 61, within the 45 casing or general support 5, is a two-part jack shaft, the two parts being illustrated at 62 and 63. The part 62 is always in connection with the drive shaft 6 through the coupling 60, and carries a gear which meshes with a complementary 50 gear upon the hammer 1, whereby the latter is rotated. In the form shown in Figure 1 the meshing gears 64 and 16 are bevel gears, whereas in Figure 3 the corresponding gears 64' and 16' are spur gears.

55 The two parts of the jack shaft are capable of being clutched together for conjoint rotation by simple clutch means. In the form shown in Figure 1 a clutch element 65, splined upon the live shaft part 62, is provided with a tapered 60 socket engageable with a tapered tip 66 on the second part 63 of the jack shaft, and is urged into engagement by a spring 67. A sleeve 68 threaded at 56 in the general support 5, within 65 and relative to which clutch element 65 rotates, serves to control engagement or disengagement of the sleeve 65 and tip 66. The sleeve 65 effects rotation of the part 63 when the tapered clutch elements are engaged by downward screwing of sleeve 68, and when such sleeve is sufficiently 70 raised by unscrewing it these clutch elements are positively separated by pressure of sleeve 68 against the flange of sleeve 65, compressing spring 67, so that it rotates freely without driving shaft 63. In the form shown in Figure 3 the tapered tip 66' is carried upon the live jack shaft

part 62, and the part 63 is provided with a complementary socket, engagement being accomplished by threading of the sleeve 63', within and relative to which shaft 62 rotates into the general support 5. Unscrewing movement of sleeve 68' lifts tip 66' positively out of engagement with its socket in shaft 63, so that its driving connection is interrupted.

In each form of the device the disconnectible jack shaft part 63 is provided with a driving gear 69, which meshes at all times with a gear 36 carried by the chuck or drill support 3. Whenever the part 63 is connected with the drive the chuck 3 is caused to rotate positively. When the parts 62 and 63 are disconnected the chuck 3 will not normally rotate. It is desired to point out that it is given no impulse to rotate by the striker, since the latter is held against rotation, and may only reciprocate in the direction of the length of the shank of the drill bit.

It is desired to point out also that the ratio between the gears 69 and 36 is such, with respect to the ratio between the gears 64 and 16, or 64' and 16', that the chuck 3 is rotated at a rate considerably slower than the hammer is rotated, which is desirable.

It is necessary, during rock drilling operations, to supply water adjacent the working tip 40 of the drill bit, and to this end the drill is provided with a central bore 41, and with outlets adjacent the point 40, which latter are not shown. Since the device as a whole is intended to be portable, water must be supplied through a flexible connection, and guided, through conduits incorporated within the device, to the hollow bore 41. The form shown in Figure 3 is particularly adapted to doing this, in that the rotative hammer 1' is coaxial with the striker 2 and with the drill 4, and therefore the water, supplied at 70, opposite the drill bit 4, may be supplied through a conduit 7, which passes through the axis of the hammer 1', through the striker 2, and its tip 71 may enter and be reasonably well packed within the bore 41. No interference with working parts is thereby entailed in any way, nor is there likelihood of intermingling of water and lubricant contained within the chamber of the casing 5. In the form shown in Figures 1 and 2 the same result can be accomplished by bending the conduit 1, as indicated at 72 in Figure 2, so that it passes around the transversely disposed hammer 1. The bend 72 may indeed embrace the hammer 1 much more closely than is illustrated, and without danger of effecting vibration or wear of the conduit by direct contact with the hammer, by reason of the fact that the hammer 1, due to its relatively great mass, has no appreciable tendency to vibrate. In the latter form the impact elements 11 need not extend the entire length of the cylindrical periphery of the hammer 1, but may be divided, as also the impact elements 21, whereby to afford space for the bend 72 between the divided impact elements, as is best seen in Figure 1.

The number of such impact elements, and consequently the number of impulses for each rotation of the hammer, is a matter which may be varied as desired. By employing the form shown in Figures 1 and 2 the surface of the hammer which carries such impact elements is increased, over the surface available in the form shown in Figures 3 and 4, and consequently more such impact elements may be employed in that surface, and more impacts may be obtained for each revolution of the hammer. By such an expedient

the rate of rotation of the hammer may be lessened without lessening the number of impacts in a given period of time.

It is desired to point out what is true in this arrangement, as in other similar arrangements, namely, that the force of each impact depends substantially entirely upon the degree to which the impact elements 21 are moved, by pressure upon the working point of the drill and transmitted through the drill to the striker, into the path of the impact elements 11. If the impact elements 21 only barely enter the path of the elements 11, then the force of each impact is but slight. If the elements 21 are pressed more deeply into the path of the elements 11, the force of each impact will be greater, and this is a matter which is wholly within the control of the operator, for he can transmit more or less pressure or resistance from the point 40 to the impact elements 11, and thereby control or vary the force of the impact from very light impact to the maximum permitted by the mass and rate of rotation of the hammer. It is desired also to point out that there are a minimum number of parts, and each part is rugged and substantial, and practically impossible to wear out, other than perhaps the hardened impact elements, which can be readily replaced, if necessary. In particular there are no springs which are necessary to the hammering operation, and consequently there is no possibility of placing the drill as a whole out of operation, due to a defect in or breakage of a spring. Because of the ruggedness and simplicity of the machine as a whole, superfluous parts may be eliminated, and though the hammer itself is of very large mass, and constitutes a large part of the total weight, the weight of the device as a whole is yet within reasonable bounds, and it can be transported and moved about in operation with all the facility required, and fatigue upon the operator is lessened by elimination, to a large degree, of vibration at the supporting handles.

What we claim as our invention is:

1. A percussion drill comprising, in combination with a casing having means to support a drill bit for vibratory movement in the direction of its length, a cylindrical rotative hammer, supported in said casing, the axis whereof is disposed transversely of the drill bit's shank, a centrally bored striker disposed within the casing to be engaged by the drill bit, and guided therein for movement under the pressure of the drill bit towards the axis of the hammer, upstanding impact elements carried by the adjacent faces of the hammer and striker, in position for engagement by such movement of the striker, upon engagement to repel the striker, and a water supply conduit entering the casing at the side opposite the drill bit, extending about the hammer, and entering the central bore of the striker, to be conducted, via a bore along the drill shank, to the working tip of the drill bit.

2. A percussion drill comprising a casing, means rotatively supported thereby for supporting a drill bit for vibratory reciprocation in the direction of its length, a rotative hammer journaled in the casing, and disposed with its axis transversely of the drill's shank, and in a plane common thereto, a striker guided within the casing against rotation, and for movement, in the direction of the length of the drill's shank, towards and from the hammer under the pressure of the drill shank engaged therewith, complementary impact members upstanding from the adjacent surfaces of the hammer and striker, in

position for engagement more or less in accordance with the extent of the advance of the striker towards the hammer, by such engagement being repelled to effect a working stroke of the drill bit, a two-part jack shaft journaled in the casing, parallel to the drill's shank, drive means to rotate one part of the jack shaft, a positive driving connection between its other part and the rotative drill-supporting means, and clutch means for operative engagement or disengagement of its two parts, at will.

3. A percussion drilling machine comprising a casing, a rotatable hammer therein, a striker mounted in said casing for unrestrained reciprocable movement, means for reciprocally mounting a drill bit in a position to be struck by said striker, and means whereby rotation of said hammer imparts blows to said striker to be transmitted by the latter to the drill bit, the weight of the hammer being approximately forty per cent of the weight of the complete machine including the drill bit when the drill bit is of a weight approximately midway between the

weights of the heaviest and the lightest drill bits which the machine is designed to use, whereby vibration of the drilling machine is largely absorbed by the hammer.

5. A percussion drilling machine comprising a casing, a rotatable hammer therein, a striker mounted in said casing for unrestrained reciprocable movement, means for reciprocally mounting a drill bit in a position to be struck by said striker, and means whereby rotation of said hammer imparts blows to said striker to be transmitted by the latter to the drill bit, the weight of the hammer being at least forty per cent of the weight of the complete machine including the drill bit when the drill bit is of a weight approximately midway between the weights of the heaviest and the lightest drill bits which the machine is designed to use, whereby vibration of the drilling machine is largely absorbed by the hammer.
